WALL CONSTRUCTION

Edward M. Hall, Omaha, Nebr.

Application December 13, 1939, Serial No. 308,985

3 Claims. (Cl. 72—30)

This invention relates to wall construction consisting of rectangular blocks adapted to be laid in horizontal courses one above another, the length, height and width of the blocks for a specific wall being uniform, but of greater or lesser proportions, depending upon the kinds of buildings to be built.

One of the objects in view is to provide very strong, reinforced blocks and reinforced walls. Also it is an object to provide blocks of such construction that all parts may be handled conveniently by a single operator who may form the blocks completely at the time they are laid in the wall, this being an advantage since a plastic concrete filler is used for each block, and thereby hardening of each block is permitted while building each course.

The invention includes dead air space or insulation for the inner side of the wall, and includes other features of advantage as will be hereafter mentioned. The invention consists of the new and useful construction, combination and arrangement of parts as described and claimed herein, and as illustrated in the accompanying drawings, it being understood that changes may be made in form, size, proportions and minor details of construction, said changes being within the scope of the invention as claimed.

In the drawings which illustrate one embodiment of the invention, Fig. 1 is a vertical section on line 1—1 of Fig. 3, said view showing a pair of blocks, partly broken away, being added to show a lower horizontal course for a wall. Fig. 2 is a sectional view showing spacing-means for maintaining the slabs or side-plates of a wall block in relatively parallel position.

Fig. 3 is a view of a block in longitudinal section on line 3—3 of Fig. 1 to clearly show stabilizing devices for a wall block.

Fig. 4 is a view in side elevation showing the use of wire-mesh for reinforcement purposes and Fig. 5 is a side view of a tool for temporary use in supporting the slabs or side-plates in parallel position.

The invention is shown and described in connection with rectangular blocks 10 adapted to be disposed one upon another in horizontal courses, the proportions or size for the blocks depending upon the height of the walls to be built and use or occupancy of the building.

Each block consists of a pair of rectangular slabs or side-plates, the outer side-plate being indicated at 11 and the inner plate indicated at 12, the rectangular area between the plates being utilized for reinforcements.

Numerals 13 and 14 indicate anchor-nuts for the respective outer and inner slabs or side-plates, the anchor-nut for the inner side-plate extending completely therethrough.

5 Numerals 15 indicate strips or sheets of wire-mesh which are embedded in the side-plates, each having end-portions 15' which extend into the area between the side-plates, and at 16 are indicated anchor-members made of wire-mesh or other foraminous material, partly embedded in the side-plates and secured by use of fasteners 17, to members 15, these members 16 having end-portions which also extend into the area between the side-plates. These sheets 15 and 16 are mounted, midway between their ends, upon the anchor-units.

10 Numerals 18 indicate eye-bolts adapted to be threaded in the anchor-nuts, and at 19 is indicated a spacing-bar having projections at its ends for engaging in the apertures of the eye-bolts.

15 Co-operating devices, such as recesses 20 formed in the horizontal edges of the side-plates and suitable locking elements 21 therein, are employed. The recesses of an upper block are disposed in register with the recesses of a lower block, and by use of members 21 the blocks of the several courses may be maintained in vertical alignment.

20 Numerals 22 indicate upright reinforcing rods and at 23 are indicated horizontal reinforcing rods, these stabilizing elements being disposed between the side-plates for the several courses of a wall, the number of these elements 22 and 23, and their spacing depending upon thickness and height of the wall.

25 Numerals 24 indicate a filler for the areas between the side-plates, and this filler and also the slabs or side-plates may consist of concrete or other suitable material.

30 The anchor-nuts 13 and 14 are disposed midway between the ends of the side-plates, and each anchor-nut 14 is threaded for receiving a supporting-bolt 25 which projects outwardly of the side-plate 12 for receiving and supporting a bearing-block 26, these bearing-blocks being adapted to support an inner plastered wall 27 or metallic lath for a wall and to provide air-insulation space 28.

35 Numerals 29 indicate a tool for temporary use of an operator when disposing the side-plates in parallel position. In operation the upright stabilizing rods 22 may first be placed in position. When the side-plates of the blocks for an upper course is laid upon the side-plates of a lower course, the recesses above mentioned may receive

the locking elements 21 so that the lower edges of the upper side-plates to be laid will be suitably supported. The tool 29 may then be used, the pairs of prongs 30 at the ends of the tool being disposed stridly, and the length of the tool corresponding to the thickness of the building block.

The side-plates being thus supported by use of the tool, it is obvious that the eye-bolts may be rotated for suitable adjustments in the anchor-nuts, and the spacing-bar when placed in operative position will maintain the side-plates relatively parallel. The tool when removed will permit a horizontal reinforcing rod to be placed in position, and the adhesive filler may then be poured or deposited, and thereafter will become hardened for holding the parts in firmly connected condition as a unit.

Numeral 31 (Fig. 4) indicates apertures formed in the wire-mesh of members 15 and 16 for receiving the anchor-nut 13 and 14.

Among some of the advantages to be derived by use of the invention it may be stated that the costly wall forms usually employed are not required. Also all expensive wall finishing may be dispensed with, and the outer slab or side-plate of each block may be finished before the block is used, and may be provided with any selected color, texture or surface treatment.

It is obvious that the wire-mesh between the side-plates of one block may extend to an adjacent block, and when the areas between the side-plates of the blocks have been filled with adhesive material, each block at its ends will be secured, on account of this construction, with the ends of blocks adjacent thereto. Since labor of only ordinary skill is required, the use of the invention will be an advantage as an expense-saving feature.

I claim as my invention:

1. In wall construction, concrete slabs laid in horizontal courses providing an outer and an inner wall-section and a channel between said wall-sections, anchor-nuts disposed opposite to each other embedded in the wall-sections and extending to the channel, eye-bolts threaded in the

5 anchor-nuts, spacing-bars spanning the channel and mounted in the eye-bolts, sheets of wire mesh mounted on the anchor-nuts each having a part embedded in a wall-section and having an end-portion extending into said channel, and concrete material in said channel for embedding therein the spacing-bars and end-portions of said sheets of wire mesh.

2. In wall construction, concrete slabs laid in horizontal courses providing an outer and an inner wall-section and a channel between said wall-sections, horizontal stabilizing-rods midway between the wall-sections, vertical stabilizing-rods in the channel intersecting the horizontal stabilizing-rods, anchor-nuts arranged opposite to each other in pairs and embedded in the wall-sections, eye-bolts threaded in the anchor-nuts, spacing-bars disposed transversely of the channel and mounted in the eye-bolts, sheets of wire mesh arranged in opposed pairs, the sheets of each pair being riveted to each other and mounted on an anchor-nut and having parts embedded in a wall-section and having relatively spaced end-portions extending into the channel, and a concrete filler in the channel for embedding therein the said reinforcing-rods, portions of the eye-bolts, the spacing-bars and said end-portions of wire mesh sheets.

3. In wall construction, rectangular, concrete slabs laid one upon another providing a pair of relatively spaced, parallel side-sections and an intermediate channel, pairs of opposed anchor-nuts in the side-sections, eye-bolts threaded on the anchor-nuts and extending into the channel, 35 spacing-bars each spanning the channel and detachably mounted on the eye-bolts of a pair of opposed anchor-nuts, sheets of wire mesh secured to each other in pairs and provided with apertures for receiving the anchor-nuts therein, the sheets of each pair having parts embedded in the side-sections and having end-portions disposed in spaced relation in the channel, and concrete material in said channel for embedding therein the eye-bolts, said spacing-bars and the spaced 45 end-portions of said sheets of wire mesh.

EDWARD M. HALL.
